Primary Examiner — Barbara Fox*Assistant Examiner* — Lilyana Bekic(74) *Attorney, Agent, or Firm* — Hauptman Ham, LLP(57) **CLAIM**

I claim the ornamental design for a medicine inhaler, as shown and described.

DESCRIPTION

FIG. 1 is a perspective view of a medicine inhaler showing the new design;

FIG. 2 is a perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the medicine inhaler that form no part of the claimed design.

1 Claim, 7 Drawing Sheets(56)
